UNITED STATES PATENT OFFICE.

JOSEPH PURDY, OF PATERSON, NEW JERSEY.

BUILDING-BLOCK.

1,236,483.

Specification of Letters Patent.

Patented Aug. 14, 1917.

Application filed February 24, 1916. Serial No. 80,148.

To all whom it may concern:

Be it known that I, JOSEPH PURDY, a citizen of the United States, residing at Paterson, in the county of Passaic and State 5 of New Jersey, have invented certain new and useful Improvements in Building-Blocks, of which the following is a specification.

One object of this invention is to provide 10 a building block or brick of rectangular form with means whereby it may interlock with a counterpart brick, and yet permit repairs to be made in a wall built of bricks so formed with the minimum impairment of 15 the integrity and strength of the wall. My invention is particularly adapted to bricks or blocks employed for the lining of furnace walls and the like, where the action of the heat and the weight of the boiler and other 20 structures imposed on the wall have to be taken into account as disturbing influences and the necessity for repairs is more or less frequent. In carrying out my invention I provide a rectangular block or brick having 25 on one of its horizontal faces a lug arranged midway between two opposite vertical faces, and a definite distance from a third vertical face, adjoining said horizontal face and also having a recess in either angle formed by 30 the other horizontal face and either of the two first-named vertical faces and the same distance from the third vertical face as the lug, each recess being a counterpart of the other, and two such adjoining recesses in 35 two such adjoining blocks being shaped to conform to one such lug on a third block.

In the accompanying drawings, Figure 1 is an isometric view of a wall for a furnace constructed in accordance 40 with this invention;

Fig. 2 is an inside elevation of said wall, partly in section;

Fig. 3 is a plan of the wall in the plane 45 of the top surface of the base-blocks;

Fig. 4 shows a course of "stretcher" bricks and Fig. 5 a course of "header" bricks, constructed in accordance with my invention;

Figs. 6 and 7 are isometric views of two 50 lining bricks, the first being for the face of the wall and the second for use in forming an angle;

Fig. 8 is an isometric view of one of the 55 header bricks; and,

Fig. 9 is an isometric view of a fragment of the base-block.

In the drawings, Fig. 1 shows a furnace wall *a* composed for the most part of bricks or building blocks *b* of ordinary form, but provided with a lining of bricks or building 60 blocks, preferably composed of fire-clay or some other vitreous material, the same being formed in accordance with this invention and in the present instance including the stretchers *c*, headers *d*, corner or angle 65 bricks *e*, and base-blocks *f*.

In general, the wall is built so that the 70 bricks in the various courses break joints with those in adjoining courses; the headers *d* of course are employed for tying or anchoring the lining in the wall formed by the bricks *b*.

Each of the stretcher bricks *c* is shaped 75 more or less like an ordinary building brick and has on one of its broad or horizontal faces an elongated rectangular lug *g* extending longitudinally of the brick, and arranged substantially in its opposite face, to wit, at each end of the brick, is formed a recess *h*, the two recesses being arranged 80 in the central longitudinal axis of the brick and being counterparts of each other, and two such adjoining recesses in two such adjoining bricks being shaped to substantially 85 conform to one lug such as *g* on a third brick. Of course, two such recesses, together, are a trifle larger than the lug received therein, so as to admit the mortar or cement used in the wall.

The header bricks *d* have the same vertical and longitudinal dimensions as the 90 stretcher bricks, but they are wider than the latter, being preferably square in plan. Their lugs *g'* and recesses *h'* are the same 95 in form as the lug *g* and recesses *h* of a stretcher brick and are arranged relatively in the same disposition excepting that they are not disposed in the central axis of the brick, but the same distance from one of its vertical faces as the lug *g* and recesses *h* are 100 from a vertical face of a stretcher brick.

In building up a wall composed of ordinary bricks *b* and the improved bricks *c* and *d* to form the lining of the wall I preferably employ several courses of the bricks *c* to one 105 of the bricks *d*, as shown in Fig. 1, the latter or headers serving as already explained to tie or anchor the lining into the body of the wall formed by the bricks *b*.

Each lug *g* (or *g'*) is received by two adjoining recesses *h* (or *h'*) of two adjoining 110 bricks *c* (or *d*), so that it will be observed

that each brick is locked by the lugs and recesses against lateral movement in any direction. This is of considerable importance, as already explained, in a structure like a furnace wall which not only supports a considerable load but is subjected to great heat and frequently to wide changes in temperature.

One important feature of my invention is 10 the fact that by forming a lug on one of the horizontal faces of the brick and substantially midway between two opposite vertical faces and a definite distance from a third vertical face and further providing counter- 15 part recesses in either angle formed by the opposite horizontal face of the brick and each of the two first-named vertical faces and the same distance from the third vertical face as the lug, the wall can be repaired 20 by removing the burnt-out or otherwise damaged bricks and replacing them with new ones so that all of the bricks so replaced but one will be interlocked by the lug and recesses. Thus, if it were necessary to replace 25 the bricks marked α and α' in Fig. 1, for all three bricks marked α new bricks can be substituted, interlocked with each other and with neighboring bricks, the same as all other bricks in the wall, and only the lug on 30 the brick which is to be substituted for the brick α' and one-half of a lug on either of the bricks marked γ would have to be cut away; for removal of the cement or mortar leaves enough clearance to permit the brick 35 to be inserted notwithstanding the lug on the other brick γ is left intact.

The bricks e for the corners are the same as the stretcher bricks e as to the form and disposition of their lugs g'' and recesses h'' , 40 excepting that one of the recesses extends into the brick at right angles thereto (see Fig. 7). Such a recess h'' , therefore, of the brick e in one course in Fig. 1 would receive the lug g'' of the brick e in the course 45 next below.

I prefer to construct a wall composed of my bricks with a base including the base blocks f . Each base-block f is rectangular in

form and approximates in thickness from its face f' to its face f'' the combined widths of 50 two stretcher bricks, or the width of one header brick. In its rear upper portion it has a rabbet f''' extending across the block and approximating in width one-half the width of the block. The wall, with the 55 bricks in the several courses breaking joints with each other, is built up back of and upon these blocks f in such manner that a series of bricks i in one of the courses projects partly into the rabbet and partly between the bricks in adjacent courses back of the base-blocks. The course of bricks next 60 above the series of bricks i preferably includes series of the headers d , which rest partly on the series of bricks i and partly on 65 the blocks f . Therefore, if any of the blocks f have to be removed, since the series of bricks i remain bound in the wall back of the blocks, they serve to support all of the wall above the block until the block can be replaced. 70

Having thus fully described my invention, what I claim as new and desire to secure by Letters Patent is:—

A substantially rectangular building block 75 having on one of its horizontal faces a lug shorter than the distance between and arranged substantially midway of two opposite vertical faces, and a definite distance from a third vertical face, adjoining said 80 horizontal face, and also having a recess in each angle formed by the opposite horizontal face and each of two of the three vertical faces aforesaid, each recess being a counterpart of the other and one of them being the 85 same distance from the third vertical face as the lug, and two such adjoining recesses in two such adjoining blocks being shaped to conform to one such lug on a third block, each of said horizontal faces being otherwise 90 in a single plane throughout, whereby in a wall formed of such bricks replacement of a number of the bricks may be effected with the minimum of removal of portions thereof.

In testimony whereof I affix my signature. 95

JOSEPH PURDY.
